PAPER DRYING APPARATUS

Marin Phillips, Appleton, Wis., assignor to The Appleton Coated Paper Company, Appleton, Wis., a corporation of Wisconsin

Application October 13, 1943, Serial No. 506,026

6 Claims. (Cl. 271—2.2)

1

The invention relates to drying apparatus and more particularly to what are known as festoon driers wherein the material is conveyed through a drying chamber in a series of loops or festoons.

Heretofore, the loop-carrying sticks have been released by having the material start the stick and pull it off, but this has been found objectionable as the desired speed cannot be obtained because of the danger of cracking the paper or injuring other material being dried and trouble experienced with sticks thrown off in different directions. The object of the invention is to improve the loop take-up mechanism of the drier by providing a positive control for the release of the stick over which the material being dried is looped. According to the present invention, the stick is released before the loop is taken up, and by continually keeping a certain amount of loop in the material at the time of release the material will never form a reverse loop but will always be slack, so that paper or other material being treated will not be cracked or injured even though the speed of the machine is increased.

The invention further consists in the several features hereinafter set forth and more particularly defined by claims at the conclusion hereof.

In the drawings:

Fig. 1 is a diagrammatic view of apparatus embodying the invention;

Fig. 2 is a detailed vertical sectional view taken on the line 2—2 of Fig. 1;

Fig. 3 is a circuit diagram of the magnet control;

Fig. 4 is a detailed sectional view taken on the line 4—4 of Fig. 2, showing the stick release mechanism in stop position;

Fig. 5 is a view similar to Fig. 4 showing the stick release mechanism in released position;

Fig. 6 is a detailed vertical sectional view taken on the line 6—6 of Fig. 4;

Fig. 7 is a detailed sectional view taken on the line 7—7 of Fig. 2.

Referring to the drawings, the material to be dried, such as the paper web P, is looped over the sticks S, and in this condition is carried by the spaced conveyors 8 in the drying zone to the spaced conveyors 9, the conveyors 8 having cleats 10 for engaging the ends of the sticks S.

From the spaced conveyors 9, the sticks S are delivered to the spaced conveyors 11 provided with cleats 12 by which the sticks are carried along to spaced guideways 13 by which they are conveyed to a box (not shown) or other suitable collector. Fig. 1 of the drawings shows one set of the conveyors and guideways for one end of the

2

sticks, and it will be apparent that similar properly spaced conveyors and guideways are provided for the other ends of the sticks, some of which are shown in Fig. 2.

5 In Figs. 4 and 7 one of the conveyors 9 is shown in detail as including an endless chain 14 associated with a grooved guide 15 in which the flattened end 16 of the stick rides while carried along by the chain 14, the weight of the paper or material being dried holding the ends of the sticks against the chain.

Usually in festoon dryers the tension of the paper or material being treated itself is used to cause a release of the foremost stick S, so that it may drop onto the conveyors 11, and this release may occur while there is little or no loop left in the material, so that a reverse loop may form therein which may cause the material to crack or be injured, particularly if it is attempted to speed up the action of the apparatus.

According to the present invention, I have provided means for positively controlling the release of the foremost stick at a definite time in the take-up period of the loop of the material being dried, so that there is always a certain amount of loop in the paper at the time this foremost stick is released. As herein shown, this means includes electromagnetically controlled stops or bars 17 for each end of the foremost stick. Each bar 17 carries a laminated armature or core 18 which forms the plunger of a solenoid electromagnet whose coil 19 is mounted on a casing 20 secured to the frame 21 of the drier.

In order to insure but one stick at a time being released, an auxiliary stop rod 22 is slidably mounted in the casing 20 and is moved by the movement of the bar 17 to a blocking position, shown in Fig. 5, before the bar 17 moves to its full release position and remains in this position until the bar 17 moves to its initial stop position. For this purpose the bar 17 has a lost motion operating connection with the rod 22 by means of a lever 23 pivoted intermediate its ends on a pin 24, one of the ends of said lever engaging in spaced slots 25 in the bar 17 and the other forked end 26 disposed between a block 27 secured to the rod 22 and a collar 28 slidably mounted on the rod 22. The collar is normally held against the end 26 of the lever by means of a compression spring 29 which also acts through the collar and the lever to move the auxiliary stop rod 22 to a release position. The collar 28 is also yieldingly connected to the rod 22 through a spring 30 interposed between said collar and a shouldered portion 31 of said rod 22.

When, however, the stop bar 17 is pulled up by its electromagnet and the lever 23 is shifted from the position shown in Fig. 4 to the position shown in Fig. 5, the bar 17 is moved up to release the foremost stick and the stop rod 22 is moved down to a position to stop the next stick from being released and at the same time the spring 29 is compressed.

With this construction, as the bar 17 is lifted upwardly by its solenoid, the lever 23 is oscillated in a clockwise direction. This, through the collar 28 and spring 30, causes a downward movement of the rod 22 to the position shown in Fig. 5. This action occurs during the first half upward movement of the rod 17. During the remainder of the upward movement of the rod 17 to its release position, the lever 23 acting on the collar 28 serves to compress the spring 30 without moving the rod 22 since under these conditions the stop portion 31 of the rod 22 is engaging the casing and the lost motion between this rod and the bar 17 is taken up through the action of said spring 30. During the return movement of the bar 17 this lost motion is first taken up to allow the bar 17 to reach a stopping position before the rod 22 is carried up by the spring 29 to a release position to allow the sticks to move to a position to bring the foremost stick S against the stop bar 17.

The coil 19 of the electromagnet is controlled by switch mechanism that is rendered operable by the action of the movement of the material itself as its loop is being taken up and at a time preferably in advance of the usual release of the stick by the loop. For this purpose the energizing means for the magnet is controlled by an electric eye controlled mechanism.

The coils 19 are supplied with current from a supply line 32 through a magnetically operated circuit closure switch 33 which is controlled by an electric eye operated circuit closure designated generally by the numeral 34 and having its light source 35 in the supply line 32, this closure being operatively connected with the supply line 32 and connected by a conductor 36 with the operating coil 39 for the switch 33 which coil is connected by a conductor 40 with the other side of the closure 34, this conductor including a pair of micro-switches 41 which are normally closed by springs 42 and are opened by the downward movement of a bar 43 connected to the switch levers 44, this downward movement being effected by the weight of a released stick S dropping onto said bar from the position shown in Fig. 4. The switches 41 are in series with the closure 34, so that when this closure is closed, the magnet coil 39 will be energized.

The supply 32 may be closed by a manually operated double pole switch 45 and the circuit for the coil 39 put in an operative condition by a manually operated switch 46.

The electric eye device 34 is adjusted to close the circuit during a dark period, that is, when no light rays can shine from the light 35 to the device 34, and with the parts shown in the position in Fig. 2, the loop of the paper P would intercept the light rays at a position below that shown in Fig. 2 and would maintain the light rays intercepted until just after the paper moved up from the position shown in Fig. 2. As soon as the light rays are intercepted from the light source 35 to the eye device 34, as when the preceding loop is in the position shown in Fig. 1, the control circuit including conductor 36 is closed and magnet 39 is energized to close the

switch 33 which then allows the current from the line 32 to pass through the solenoid coils 19, thus drawing up the bars 17 at the ends of the foremost stick S which then drops by gravity from the conveyors 9 onto the conveyors 11, and in dropping it strikes the bars 43 at each end of the stick and thus opens the switches 41 and consequently the control circuit including coil 39, so that the switch 33 is open and the solenoids

19 de-energized and the bars 17 again lowered to a stop position ready to repeat the cycle. As soon as the paper reaches the position in which the light rays from the source 35 to the device 34 are again allowed to pass the circuit through the device 34 is open, so that it is not possible to again operate the coils 19 until the condition of darkness is restored or until the condition of the paper necessitates the release of another stick.

It is further to be noted that the bar 43 along which a released stick is carried provides a certain time element in which the released stick will hold the circuit closure 41 open, and this is provided to prevent getting more than one stick released at a time since with these closures 41 open no more sticks can be released until the paper or other material being treated is in a condition to have the light to the device 34 well interrupted. Thus the time element provided by the bars 43 prevents the loop of material from stopping on what might be termed the edge of the light beam from the source 35. Thus the point in the take-up of the loop or festoon at which the stick is released in order to start the taking up of another loop is definitely controlled and occurs before the paper itself tends to release the stick. This permits the stick to be released relatively early during the take-up of the loop which allows the loop take-up mechanism to be speeded up over the usual practice and thus increases the out-put of the drier apparatus.

I desire it to be understood that this invention is not to be limited to any specific form or arrangement of parts except in so far as such limitations are included in the claims.

What I claim as my invention is:

1. In a drying apparatus wherein the material is carried in loops on sticks conveyed through the drier, the combination of a reciprocatory stop for arresting the movement of the foremost stick, a reciprocatory stop for arresting the movement of the sticks succeeding the foremost stick until after said stick is released, an operating connection between said stops including a lever operable by said first named stop and a yielding drive connection between said lever and second named stop to permit lost motion between said stops and return said first named stop to its arresting position, and means for positively moving said first named stop to a release position when the preceding loop of the material has reached a predetermined loop position.

2. In a drying apparatus wherein the material is carried in loops on sticks conveyed through the drier, the combination of a stop for arresting the movement of the foremost stick, means for positively releasing said stop when the preceding loop has moved to a predetermined looping position, and means directly actuated by the released stick for delaying subsequent actuation of said release means to release said stop until said preceding loop is taken up to a predetermined position.

3. In a drying apparatus wherein the material is carried in loops on sticks conveyed through the drier, the combination of a stop for arresting the

movement of the foremost stick, an electromagnet for releasing said stop, a current supply circuit for said electromagnet including an electrically operated switch, a control circuit for said switch including circuit closing switch mechanism rendered operative when the preceding loop of material has been taken up a predetermined amount to thereby release said stop to release a stick, and circuit opening mechanism in said control circuit including a member of predetermined length moved by the release stick to operate said circuit opening mechanism while moving along said member and thereby rendering said control circuit inoperative for a predetermined period after the release of said stick.

4. In a drying apparatus wherein the material is carried in loops on sticks conveyed through the drier, the combination of a stop for arresting the movement of the foremost stick, an electromagnet for releasing said stop, a current supply circuit for said electromagnet including an electrically operated switch, a control circuit for said switch including circuit closing switch mechanism rendered operative when the preceding loop of the material has been taken up a predetermined amount, and circuit opening mechanism in said control circuit operable by the released stick and including a timing member engaged by said stick, said circuit opening mechanism rendering said control circuit inoperative for a predetermined period after the release of a stick.

5. In a drying apparatus wherein the material is carried in loops on sticks conveyed through the drier, the combination of a stop for arresting the movement of the foremost stick, an electromagnet for moving said stop to its release position when the preceding loop of the material has reached

a predetermined loop position and having its armature directly connected to said stop, a stop for arresting the movement of the sticks succeeding the foremost stick until after said stick is released and having a lost motion connection with said first named stop, and means for positively moving said first named stop to its arresting position.

5 6. In a drying apparatus wherein the material is carried in loops on sticks conveyed through the drier, the combination of a stop for arresting the movement of the foremost stick, a stop for arresting the movement of the sticks succeeding the foremost stick until after said stick is released, said first named stop in stopping position extending beyond the center of an arrested stick while said second named stop in blocking position does not extend beyond the center of an arrested stick, means for positively moving said first named stop to a release position when the preceding loop of the material has reached a predetermined loop position, and means for moving said second named stop to a blocking position before the first named stop has moved to a position at which stick release can take place and holding said second named stop in this position until the first stop moves to a blocking position.
